WASHING MACHINE

Charles T. Childers, Galesburg, Ill.

Application March 29, 1934, Serial No. 718,026

4 Claims. (Cl. 68—19)

This invention relates to washing machines and more particularly to washing machines of the "pounder" type.

An object of the invention is to provide a washing machine of the type referred to having a novel operating mechanism so arranged and constructed as to provide a greater mechanical operating advantage as the washer element approaches the end of the up stroke than during the first part 10 of the up stroke, thereby facilitating lifting of the element.

Another object is to provide a washer having operating mechanism of the kind referred to and including means for effecting rotary movement 15 of the pounder during reciprocation thereof.

A further object is to provide a washing machine of the character referred to having novel and improved means for adjustably supporting a mechanism frame at different heights above 20 the tub in accordance with the amount of material being washed.

Other and more specific objects will become apparent from a reading of the following description, the appended claims, and the accompanying 25 drawing, in which:

Figure 1 is a top plan view of a washing machine embodying the invention;

Figure 2 is a vertical sectional view taken on the line 2—2 of Figure 1;

Figure 3 is a detail top plan view of a suction cup supporting spider; and

Figure 4 is a detail sectional view taken on the line 4—4 of Figure 2 and drawn on an enlarged scale.

My invention may be embodied in either power operated or manually operated washing machines, and for the purpose of illustration is shown as being embodied in a washing machine comprising a tub A, a pounder or washing element generally designated B, and manually operable mechanism generally designated C for effecting working movements of the pounder B.

The tub A may be supported by any suitable means as by spaced members 1 and preferably is 45 equipped with a removable drain fitting 2 adapted to be closed by a stopper 3.

Supporting members 4—4 are removably secured to the tub at diametrically opposed points by means of bolts 5. Each supporting member 50 4 is provided with a plurality of superposed ledges 6 which extend inwardly considerably beyond the inner surface of the tub side walls and with upper and lower lugs 7 and 8 respectively which extend inwardly beyond the ledges 6.

55 A mechanism supporting frame member 9

whose length is preferably somewhat less than the inside diameter of the tub is adapted to be supported by its opposite ends resting upon the ledges 6 at a selected height whereby the height of the frame member 9 may be varied in accordance with the size of the "wash," i. e., the amount of clothes or other material in the tub. Pins 10—10 passing through registering openings in the lugs 7 and 8 and the ends of the frame member 9 serve to maintain the latter against 10 accidental displacement. By reason of the ledges extending inwardly beyond the inner surface of the tub and the length of the frame member 9 being less than the inside diameter of the tub, the frame member may easily be laid flat in the 15 bottom of the tub for shipment or storage. The supporting members also may be removed and stored within the tub.

The frame member 9 is provided with a boss 10^a bored to form a guide for a vertically reciprocable staff 11 on the lower end of which is removably mounted a three armed spider 12 which may be held in position on the staff by any suitable means such as a cotter pin 13. Suction cup 20 pounder elements 14 are removably secured respectively to each arm of the spider by means such as wing nuts 15. The upper end of the staff 12 is formed with a slot 16 in which is positioned a roller 17 journaled on a pin 18 extending across the slot, the roller being located somewhat above 30 the bottom of the slot so as to provide a space between the bottom of the roller and the bottom of the slot. It will be observed that the roller is substantially flush with the sides of the slot so that the roller-equipped end of the staff may 35 be withdrawn from the guide to permit disassembly and packing of the staff, the spider, and the suction cups within the tub.

It is apparent that when in use the degree of 40 vacuum in the suction cups 14 will increase as the spider and cups are raised from their lower to their upper positions, the vacuum being greatest just as the suction cups approach their uppermost positions. Consequently the force required to lift the suction cups will become greater 45 as the cups ascend. In order to obtain easy operation without unduly sacrificing speed I provide operating mechanism adapted to provide a greater mechanical operating advantage toward the end of a lifting stroke than at the beginning thereof.

In the form shown I provide a vertically extending bifurcated bracket 19 secured as at 20 to the frame member 9 adjacent the boss 10^a. An operating lever 21 is pivoted as at 22 to the 55

bracket 19, one arm 23 of the lever being adapted for manual or power operation and the other arm 24 being curved and extending through the slot 16 below the roller 17. The surface 25 of the arm 24 constitutes a cam surface engageable with the roller which acts as a follower so that when the operating lever is moved in a counter clockwise direction the staff and pounder assembly will be raised, and vice versa. The shape of the cam surface 25 is such that the mechanical advantage of the operating lever increases progressively as the staff and suction cups are raised.

In order to obtain the most efficient operation, the position of the suction cups should be shifted horizontally to a small extent at the end of each suction stroke. To this end I provide a plurality of recesses 26 in the upper face of the spider 12 disposed in a circle about the staff 11, and a pawl 27 pivoted as at 28 on the frame member 9, the nose of the pawl being adapted to engage in the recesses 26 successively when the spider approaches the end of suction strokes. Continued upward movement of the spider moves the pawl toward a horizontal position, the nose of the pawl moving to the left as viewed in Figure 2, whereby the spider and suction cups will be rotated through a small angle.

It will be apparent that a washing machine constructed in accordance with my invention embodies the advantages of simple and inexpensive construction and ease of operation. A further advantage is that all parts other than the tub itself may easily be removed and conveniently packed within the tub for shipment or storage. The washer shown in the drawing embodies the invention in practical and the at present preferred form but it will be understood that various changes may be made in the specific construction and relative arrangement of the parts without departing from the invention as defined in the claims.

I claim:

1. In a washer, the combination of a suction cup washer element, means mounting said element

for vertical reciprocating movement; an operating member; and cam and follower connections between said member and said means, the control of the operating face of the cam being such as to effect a greater mechanical driving advantage nearing the upper end of a suction creating stroke than at the beginning thereof.

5

2. In a washer, the combination of a suction cup washer element, means mounting said element for vertical reciprocating movement; an operating member; and connections between said member and said means adapted to effect a greater mechanical driving advantage nearing the upper end of a suction creating stroke than at the beginning thereof, said connections including a cam movable with said operating member, and a follower connected to said washer element and engaging said cam.

15

3. In a washer, the combination of a frame member formed with a guide; a staff mounted for vertical reciprocating movements in said guide and extending through and beyond opposite ends thereof; a washer element mounted on one end of said staff for swivelling movements relative to the staff, there being a slot formed in the other end of the staff; a roller mounted for rotation in said slot; and an operating lever pivoted to said frame member and having one of its ends formed as a cam, the cam extending through the slot in said staff and engaging said roller.

20

4. In a washer, the combination of a tub; companion supporting means secured to the tub on opposite sides thereof and being formed with a plurality of superposed horizontal ledges; a frame the opposite ends of which are adapted to be supported on said ledges of the respective supporting means to vary the height of the frame above water in the tub, the frame and said supporting means being provided with registering openings; pins extending through said openings for preventing accidental displacement of said frame; and washing mechanism mounted on said frame.
